ABSTRACT OF THE DISCLOSURE

A water tank capable of preventing stagnation and comprising a plurality of turns of a spiral channel of uniform cross-section on a concrete base, the channels being formed by a concrete wall wound in a number of turns with a constant radial distance between them and upstanding from the concrete platform so as to support the roof. A pair of inlets at one end of the spiral selectively delivers cold and warm water to upper and lower points of the channel while the other end is provided with means for withdrawing water from the tank.

The invention relates to a water-tank for water supply plants, wherein water is supplied to the tank by inflow pipes and withdrawn from the tank by outflow pipes.

Earlier containers of this kind, with a four-cornered or circular horizontal plant, or configuration had the serious disadvantage that continuous exchange or replacement of the contents was not guaranteed. On the contrary, as a result of the difference in temperature between incoming water and that already present in the tank, the water freshly added is removed earliest, whereas a portion may remain in the tank for a very long time. Though efforts have already been made to eliminate this disadvantage by baffles, often uncontrollable flow at the bottom of the tank is caused by these walls so that here, too, a portion of the water is not withdrawn for a long time.

It is an object of the invention to eliminate these disadvantages of conventional tanks. This object is achieved by forming the tank so that conducting walls arranged as a spiral pipe are provided, the pairs of adjacent conducting walls forming a canal, preferably of the same cross-section, connecting the inflow and outflow pipes.

In accordance with this invention, water may flow through the tank in one sense of rotation at a time only, whereby, as practice has shown, the continuous exchange or replacement of the whole tank capacity is ensured.

The spiral conducting walls according to the invention are formed as load-bearing walls. When the outside walls only are load-bearing walls, the entire load of the empty tank must be taken up by the border foundations and a cover or roof with a large span is necessary. Owing to the great expanse of the bottom or floor of the tank between the load-bearing walls, the bottom cannot be concreted in a single operation and leakage from the tank always results in spite of the considerable consumption of material.

According to the invention, it becomes possible to distribute the load over the entire cross-section so that a relatively thin bed plate suffices, thereby allowing a considerable saving in reinforcing bars and concrete, the tank, moreover, being tight. Furthermore, roof span is reduced so that pre-fabricated covers, which may be placed with essentially higher speed, can be used. The walls, which need take up relatively small loads, are constructed by the Torcret system which involves applying high-grade concrete in a single shell. Concrete injected by the Torcret (pneumatic gunite) system does not need any finishing and is sufficiently water-tight.

2

By way of example, an embodiment of the invention illustrated in the drawings is described more fully below; in the drawing:

FIG. 1 shows a horizontal plan view (roof removed) of a tank according to the invention; and

FIG. 2 is a cross-sectional view taken on line II—II of FIG. 1.

According to FIG. 1, the tank has spiral walls 1, assembled by quadrants. The spiral is thus formed with a first quadrant with a radius R_1 drawn with a predetermined radial distance d between two turns of the wall 1, followed by the second quadrant with a larger radius R_2 , both quadrants having a common tangent at the point in which they join. The third quadrant R_3 and the fourth quadrant R_4 follow in the same manner. The next turn of the first quadrant R_5 has a radius of R_1+d , the radius R_6 of the second turn of the second quadrant being equal to R_2+d . The other two radii are also enlarged by d relative to the third and fourth radii, R_3 and R_4 whereas each radius of the following four quadrants is larger by $2d$ than the first four arcs.

In the example according to the drawing, the tank as a whole consists of two spiral chambers, i.e., the inner chamber 2 and the outer chamber 3. Both chambers are formed by a dividing wall 4, dividing the whole spiral into two parts. An outlet chamber 5 joined to the dividing wall 4 is connected with the inner chamber 2 by a conduit 6 and with the outer chamber 3 by a conduit 7. The conduits 6, 7 extend into a valve chamber 8, located at the end of the spiral and may be blocked alternatively by valves 9, 10, respectively, disposed in this chamber. Water is withdrawn from the chamber 5 by a conduit 11.

The water is supplied by a conduit 12 divided into two branches 13 and 14, branch 13 feeding the inner chamber 2, branch 14 the outer chamber 3. The conduits 13, 14 may be blocked by valves 15 and 16, an overfill of both chambers being prevented by valves 17 and 18 controlled by floats.

FIG. 2 illustrates that feeding of the outer chamber 3 may be realized through an upper inlet 19 as well as through a lower inlet 20. The inlet 19 may be blocked by a valve 21, the inlet 20 by a valve 22. The possibility of double feeding has the advantage that in summer, the incoming water, which is colder than that within the tank capacity, may be supplied through the upper inlet 19 so that this cooler water moves downwardly during circulation in the tank; in winter, the warmer water is supplied through the lower inlet 20 and rises during circulation. Therefore, a mixing up of the tank capacity is also ensured in vertical direction.

As may be seen from the drawing, the distance (d) between the individual load-bearing walls 1 is relatively small so that it is possible to concrete the bottom from wall to wall in a single operation. Shrinkage gaps extending through the total construction are closed by concrete using the Torcret system when the concrete has set. Tightness of the tank is thus essentially increased. Moreover, a stagnation of the tank capacity is efficiently avoided as the water circulates only in one direction. Of course, this circulation of water is not only attained with the embodiment shown, but also with other spiral embodiments of the conducting walls, e.g., concentric annuli.

I claim:

1. A water tank comprising a generally horizontal base, spiral wall means upstanding from said base and defining therewith at least one spiral channel extending over a plurality of turns and of uniform horizontal width, inlet means for delivering water to said channel at one end thereof, and outlet means for withdrawing water from said channel at the other end thereof, said inlet means including an upper inlet and a lower inlet opening into

said channel at said one end thereof, and means for selectively operating said inlets to deliver cold water to said channel at said upper inlet and warm water to said channel at said lower inlet.

2. A water tank comprising a generally horizontal base, spiral wall means upstanding from said base and defining therewith at least one spiral channel extending over a plurality of turns and of uniform horizontal width, inlet means for delivering water to said channel at one end thereof, and outlet means for withdrawing water from said channel at the other end thereof, said tank is being provided with a roof, said wall means including a single load-supporting vertical wall extending in a plurality of spiroidal turns spaced apart by a constant horizontal distance and supporting said roof.

3. The water tank defined in claim 2 wherein said inlet means includes an upper inlet and a lower inlet opening into said channel at said one end thereof, and means for selectively operating said inlets to deliver cold water to said channel at said upper inlet and warm water to said channel at said lower inlet.

4. The water tank defined in claim 2 wherein said base and said wall means are composed of concrete.

5. The water tank defined in claim 2, further comprising partition means extending across said channel and sub-dividing same into a plurality of individually generally spiral channel sections, said inlet means and said outlet means communicating with said sections to induce water flow therein over substantially equal distances in opposite senses.

6. The water tank defined in claim 5 wherein said inlet

means includes an upper inlet and a lower inlet at one end of one of said sections and means for selectively operating said inlets for delivery of relatively warm water to said one of said sections at said lower inlet and relatively cool water to said one of said sections at said upper inlet.

7. The water tank defined in claim 6, further comprising float-controlled valve means in each of said sections connected with said inlet means for controlling the influx of water thereto.

8. The water tank defined in claim 5 wherein said outlet means includes a chamber along said partition means, conduit means connecting each of said sections with said chamber, and valve means in each of said conduit means for selectively discharging water from said sections into said chamber.
